UNITED STATES PATENT OFFICE.

NELSON LEDUC AND ALBERT E. WEEKS, OF LOCKPORT, NEW YORK; SAID WEEKS ASSIGNOR TO SAID LEDUC.

DUST-COLLECTOR.

SPECIFICATION forming part of Letters Patent No. 401,503, dated April 16, 1889.

Application filed March 5, 1887. Renewed February 2, 1889. Serial No. 298,513. (No model.)

To all whom it may concern:

Be it known that we, NELSON LEDUC and ALBERT E. WEEKS, citizens of the United States of America, residing at Lockport, in the county of Niagara and State of New York, have invented certain new and useful Improvements in Dust-Collectors, of which the following is a specification, reference being had therein to the accompanying drawings.

10 This invention pertains to certain new and useful improvements in dust-collectors; and it consists in the detailed construction and combinations of the parts, substantially as hereinafter fully set forth, and particularly 15 pointed out in the claims.

In the accompanying drawings, Figure 1 is a view in perspective of our invention with the upper portion or cover raised. Fig. 2 is a vertical transverse sectional view thereof.

20 Fig. 3 is a vertical sectional view on the line $x x$, Fig. 2.

In carrying out our invention we secure within supporting framing a an approximately V-shaped dust-receiving chamber or receptacle, A, the same having the upper ends of its side walls secured to horizontal side bars, a' , of said framing. To the lower convergent sides of this chamber or receptacle are secured the sides of a box or casing, a^2 , 30 the same extending from end to end of said chamber or receptacle, the purpose and more minute construction of which will appear farther on. This chamber or receptacle has two similarly-arranged partitions, $b b$, secured 35 a short distance from each other at equal distances from the ends of the machine, thus forming at the center a still-air chamber, B, and two equal-sized compartments, $b'' b''$, at the ends. These partitions $b b$ have each two 40 eccentric openings, b' , formed therein, the purpose of which will also be stated farther on.

C C' are two vertical parallel boards or deflectors running lengthwise the machine, the same being secured to the partitions b and 45 the ends of the compartments of the V-shaped chamber or receptacle. These deflectors are so arranged that their lower ends are one within a short distance of the inner surface of one of the inclined sides of the chamber or 50 receptacle and the other directly over the cen-

ter thereof, a short distance from the opening into the box or casing a^2 .

Within each compartment b'' is arranged the lower half or section, d , of a circular jacket, D, the same being secured at its ends to the 55 central partition, b , and the end walls of the machine. These halves or sections d are composed each of a solid piece of metal, d' , and an open or slatted portion, d^2 , as shown in Fig. 2. Before describing the purpose of these 60 jackets and the detailed construction of the parts operating therein reference will first be had to the upper portion or cover, E, which is essential to the complete construction of and forms part of our invention. This cover E 65 has semicircular ends, and has projecting from its upper surface to one side thereof on a horizontal line an inlet-trunk, e , extending the entire length of said cover.

In the cover E are secured two partitions, 70 $b^3 b^3$, corresponding to the partitions $b b$, and the space formed between said partitions b^3 b^3 is covered by cross-strips connected to the lower ends thereof. The upper halves or sections, e' , of the circular jackets D are constructed and secured in a manner similar to the lower halves or sections—namely, of a piece of solid metal, d' , and an open or slatted portion, d^2 , secured at their ends to the central partitions, $b^3 b^3$, and the end walls of the 75 cover. Both the upper and lower halves or sections of the circular jackets D are arranged so as to form on the top forward side and under surfaces of said jackets continuous passages or flues ff . The other or rear side of 80 each of said jackets—namely, the side composed of solid metal—is closed at its upper and lower ends, respectively, by means of the inlet chute or trunk and a horizontally-disposed partition, f' , as seen in Fig. 2. A draft-regulating damper, f^2 , is located within the 85 long inlet-trunk, as shown.

The ends of the chamber or receptacle A and the cover E, as well as the upper and lower central partitions, have large semicircular openings $E'E^2$ formed therein, the opening E^2 of the upper central partitions, $b^3 b^3$, being lined with tin or other metal. The 90 large circular openings E' at each end of the machine, formed by the cover being closed or 95 100

fitted thereon, have wire screens *g g* secured over the same.

5 G is a central horizontally-disposed shaft extending through the above-described circular openings of the machine and supported by curved brackets *g'*, in the upper outer ends of which are formed ordinary journal-boxes, *g²*, wherein the ends of said shaft are disposed.

10 H H are two sets of fans, each set being secured by ordinary means to the shaft G, said fans being designed to revolve within the circular jackets D D, through the slotted portions of which jackets the agitated air is forced 15 by said fans into the passage or flues *ff*. To one end of this shaft is secured a band-wheel, *h*, whereby power is transmitted to said shaft, the working of the machine being effected in any known way and in any desired manner.

20 To the other end of this shaft is secured a band-wheel, *h'*, over which passes a driving-belt, *h²*, which also encompasses a band-wheel, I, secured upon the outer end of the shaft of a continuous valve, I'. The valve I' is constructed by cutting or removing portions of a 25 shaft forming cavities *i*, which when in a registering position form the lower curved end of the V-shaped chamber or receptacle. The ends of the shaft of this valve project 30 through and rest in suitable apertures formed in the end walls of the inclosing-casing, and on the end whereon the band-wheel I is secured is also made fast a gear-wheel, *i'*, between said band-wheel and the casing. This 35 gear-wheel *i'* gears with a similar wheel secured on the projecting end of the shaft of a screw conveyer, J, which, as will be seen by reference to Fig. 2, is disposed in a lower compartment of the box or casing, into which 40 lower compartment opens the upper compartment, wherein is disposed the continuous valve I'.

45 One end of the conveyer box or casing has a small extension, *j*, which is provided with an opening on its under side, permitting the discharge of dust from said conveyer.

50 L L are two brushes secured upon the revolving shaft G in such manner as to cause the fibers thereof to bear against the screens *g g*, and in the revolution of the shaft the brushes will be continuously moving over the inner surfaces of said screens.

55 The operation of my invention is as follows: The upper portion or cover being first secured in position over the dust-receiving chamber or receptacle, so as to cause the upper halves or sections of the circular jackets to fit snugly at their meeting edges, the damper in the trunks is arranged so as to regulate the inflow 60 of the dust-laden air. The dust-laden air, being forced in through the trunk *e* by a suitable blast, passes along the flues *f* and down past the deflectors C C', where its maximum portion of dust is deposited in the recess or cavity of valve I'. From the lower edges of said deflectors the air rises to the openings *b'*,

through which it passes into the still-air chamber B, and thence from the top thereof into the fan-chambers through the openings E². Here the air is given a rotary motion by the fans H, 70 and the remaining dust-particles sharing in such motion are thrown by centrifugal force against the jacket D. Through the slatted portion of this jacket the dust-particles and some air pass into the flues *f*, where they unite with the current of flowing dust-laden air and share 75 with it the separating action of the deflectors C C'. The remainder of the air in the fan-chambers, which is now almost entirely purified, passes out through the screens *g*, being forced along by the pressure of the current 80 entering the trunk *e*. Whatever dust clings to the screens *g* is removed by the revolving brushes L. The centrifugal force imparted to the dust-particles by the passage of the dust-laden air through the curved flues *f* tends to 85 throw said particles to the exterior walls of such flues, and so begins the separating action. This centrifugal tendency is aided by the slight air-current issuing from the fan-chambers through the slatted jackets, the tangential arrangement of the slats giving to such current a forward as well as a radial motion. The separated dust falls through the bottom 90 of the V-shaped chamber or receptacle into the registering-cavity of the long continuous valve, which, being in motion, by means of the belt *h²*, encircling the band-wheel of its shaft, as before explained, will be caused to revolve and empty the contents of each cavity into the 95 conveyer-casing.

The screw conveyer has motion transmitted thereto by reason of the gear-wheel of the valve-shaft engaging with the similar wheel on the shaft of said conveyer. By means of 100 the screw conveyer the dust will be worked or forced toward the discharge end of the box or casing, where it will be discharged through an opening in the partition wherein the end 105 of the conveyer-shaft rests, and from this point can be conducted in any manner by a pipe or chute to the outside of the building.

From what has been stated it will be seen that by means of our invention the separation of the dust from the air is readily effected by mechanism simple in its construction and arrangement, and the parts are not liable to get out of order or to become disarranged. It will also be observed that by means of the damper in the trunk the draft 110 can be regulated as may be desired.

Having thus fully described our invention, what we claim, and desire to secure by Letters Patent, is—

1. The herein-described dust-collector, consisting of the V-shaped chamber or receptacle, the still-air chamber having openings in its side walls, the continuous valve and the inclosing box or casing therefor, the deflectors, the shaft having fans, the cover provided 115 with trunks, the screen-covered openings, the circular slatted jackets, and the gearing and 120

driving wheels, the whole arranged to operate substantially as shown and described, and for the purpose specified.

2. The combination, with the chamber or receptacle and the cover having openings at the ends, of the still-air chamber having openings in its side walls, the deflectors, the circular slatted jackets, and the fans, substantially as shown and described.

10 3. The combination, with the chamber or receptacle provided with openings at the ends and the cover, of the circular jackets secured therein having slatted and closed portions, the operating-fans inclosed in said jackets, and the still-air chamber having openings in its side walls, substantially as shown and described.

4. The combination, with the chamber or receptacle provided with openings at the ends, the cover, the circular jackets, and the fans, 20 of the still-air chamber having openings in its sides and the deflectors arranged one a short distance from the other, substantially as shown, and for the purpose described.

In testimony whereof we affix our signatures 25 in presence of two witnesses.

NELSON LEDUC.
ALBERT E. WEEKS.
